(57) **CLAIM**

The ornamental jewelry cluster design, as shown and
described.

DESCRIPTION

FIG. 1 is a front elevational view of first embodiment of a
jewelry cluster design showing my new design;

FIG. 2 is a top plan view thereof;

FIG. 3 is a front elevational view of a second embodiment
thereof; and,

FIG. 4 is a top plan view thereof.

It being understood that the broken lines are for illustrative
purposes only and form no part of the claimed design.
